1867 - VOL. III.

United States Patent Office.

ANDREW BUCKHAM AND JOSEPH EVANS, OF NEWARK, NEW JERSEY,
ASSIGNORS TO ANDREW BUCKHAM.

Letters Patent No. 61,710, dated February 5, 1867.

IMPROVEMENT IN TINSMITHS' SEAMING MACHINE.

The Schedule referred to in these Letters Patent and making part of the same.

TO ALL WHOM IT MAY CONCERN:

Be it known that we, ANDREW BUCKHAM and JOSEPH EVANS, both of the city of Newark, in the county of Essex, and State of New Jersey, have invented an improved Seaming Machine for Tinsmiths' Use; and we do hereby declare the following to be a clear and exact description thereof, reference being had to the annexed drawings, making a part of this specification, in which—

Figure 1 is a side elevation; and

Figure 2 a front elevation of the machine.

Figure 3 is a representation of the manner in which the lock is applied to the guide-plate preparatory to being closed by the die; and

Figure 4 is a representation of the lock after it has been closed by the die.

Corresponding letters of reference indicate like parts.

This invention consists in the employment of a perpendicular-acting die, A, figs. 1 and 2, the under side of which is cut out to form such shape of seam as may be wanted. This die works in combination with and is guided by a plate, B, fig. 1, which plate also acts as a stop or gauge for the lock, and is adjustable with reference to its distance from the revolving mandrel, C, fig. 1, so as to allow seams of different thicknesses to pass through when closed. The revolving mandrel C, fig. 1, is made with one or more flat or grooved surfaces forming the bed of the die, and can be used with flat or grooved, straight or curved dies, as occasion requires. D, fig. 1, is a sliding gauge, used as a stop, and to keep the ends of the locks even. The die is attached to a rod or bar, E, fig. 1, working in guides F F, and is operated by means of the lever G, and link-rod H, connecting with the foot-lever I. The spring J serves the purpose of raising the die when the foot is lifted from the lever.

The manner in which our invention is used is as follows: The locks being first prepared in the usual manner, the operator places one piece on the mandrel by sliding it under the guide-plate, the edge of the lock being up; he then hooks on another piece and draws the lock close against the guide-plate, as shown in fig. 3, being careful that the ends touch the sliding gauge; he then causes the die to descend smartly by means of the foot-lever, which closes the lock, as shown in fig. 4; the foot is then raised from the lever and the die recedes from the seam, which is now capable of being drawn under the guide-plate. Another piece is then hooked on and the operation continued until the work is completed. What we consider of advantage in our invention is, that with it seams can be formed at one operation, making it unnecessary afterwards to flatten the seam by mallet, and it is scarcely possible with it to make a false seam, as is so often the case with the machines now in use. We do not restrict ourselves to the particular form of the machine as shown in the drawings, nor to the particular shape of the die face as there exhibited; the same being made of different shapes, according to the class of seams required, being either flat, grooved, straight, or curved, as the case may be, when used with a corresponding match-bed in the revolving mandrel.

What we claim as our invention, and desire to secure by Letters Patent, is—

1. The die A, figs. 1 and 2, in combination with the guide-plate B, figs. 1 and 2, when constructed in the manner and for the purposes set forth.

2. The revolving mandrel C, and sliding gauge D, figs. 1 and 2, in combination with the die A, and guide-plate B, when constructed in the manner and for the purposes set forth in the above specification.

ANDREW BUCKHAM,
JOSEPH EVANS.
